UNITED STATES PATENT OFFICE

NICOLA F. SAVIANO, OF BROOKLYN, NEW YORK, ASSIGNOR TO CHARLES C. ORCUTT, OF NEW YORK, N. Y.

BOTTLE-CORKING MACHINE

Original application filed October 19, 1926, Serial No. 142,537. Divided and this application filed July 12, 1928. Serial No. 292,260.

- This invention relates to a bottle filling and corking machine, and more particularly concerns apparatus for automatically corking or closing bottles or other small containers.
- 5 In the packing of large quantities of small articles, such as medical pills or pellets in small containers, such as bottles, it has been found economical and otherwise desirable to employ automatic packing machinery. It is essential that machinery of this type be arranged to perform the packing operations continuously and rapidly, and that the machine be capable of operating with a minimum amount of manual attention.
- 10 With the above and other considerations in mind, it is proposed in accordance with the present invention to provide a bottle corking machine, and, more specifically, it is proposed to provide a machine of this type in which
- 15 corks or other closure members are automatically inserted and pressed within the necks or orifices of bottles, vials or other containers.
- 20 Various other specific objects, advantages and characteristic features of the present invention will become apparent as the description thereof progresses.
- 25 This application is a division of my co-pending application, Serial No. 142,537, filed October 19, 1926.
- 30 In describing the invention in detail, reference will be made to the accompanying drawings, in which:
- 35 Figure 1 is a side elevation of the bottle filling and corking mechanism, a portion of a bottle feeding mechanism being shown in a section taken along the line 1—1 of Fig. 2;
- 40 Fig. 2 is a plan view, partly in section, of the bottle filling and corking mechanism;
- 45 Fig. 3 is a side view of a development of the bottle corking mechanism;
- 50 Fig. 4 is a sectional view taken along the line 4—4 of Fig. 6 and viewed in the direction of the arrows;
- 55 Fig. 5 is a view similar to Fig. 4 showing portions of the bottle filling and corking drums in slightly different relative positions;
- 60 Fig. 6 is a sectional view taken along the line 6—6 of Fig. 3 and viewed in the direction of the arrows;
- 65 Fig. 7 is an enlarged plan view of a portion of the bottle corking mechanism;
- 70 Fig. 8 is a sectional view of the bottle corking mechanism, showing a section of the corking drum taken along the line 8—8 of Fig. 3;
- 75 Fig. 9 is a plan view of a portion of the bottle corking mechanism in the position in which a cork is about to be dropped into a bottle;
- 80 Fig. 10 is a sectional view taken along the line 10—10 of Fig. 9;
- 85 Fig. 11 is a sectional view of the cork depressing apparatus including a sectional view of the corking drum taken along the line 11—11 of Fig. 3; and
- 90 Fig. 12 is a view of a modified form of corking plunger, together with a cam for actuating the plunger.
- 95 Referring to the drawings, and more particularly to Figs. 1 and 2, the machine disclosed includes a bottle feeding mechanism, generally indicated at FD and A, a bottle filling mechanism, including the apparatus H and BF and a bottle corking mechanism including the apparatus CD. The bottle feeding mechanism is described and claimed in my copending divisional applications Serial No. 292,258 filed July 12, 1928, and Serial No. 292,259 filed July 12, 1928, and the bottle filling mechanism is described and claimed in my copending application, Serial No. 142,537. The bottle feeding and filling mechanisms form no part of the present invention and will not be described in detail herein, it being sufficient to explain that empty bottles are continuously fed to the notches 15 in the peripheral edge of the bottle filling drum BF by the bottle feeding mechanism A, and that these bottles are filled with pills, pellets or any other material as they pass around the filling drum.
- 100 Referring now more particularly to the bottle corking mechanism of the present invention, a vertical shaft 72 is journaled in a flanged sleeve 73, suitably secured to the platform 1, this shaft being keyed or otherwise rigidly secured to a corking drum CD. The drum CD is provided with an outwardly extending flange 74 at its upper end, and is pro-

vided with a plurality of aligned spaced extensions 75 integral with or suitably secured to its cylindrical surface beneath this flange. The vertical dimension of the extensions 75 is arranged to be less than the height of the bottles to be corked. The spaces between the extensions 75 are arranged to form equally spaced substantially U-shaped peripheral notches 76 on the drum, these notches being equal in number to the notches 15 on the periphery of the bottle filling drum BF. The shaft 72 is rotated in a counter-clockwise direction, as viewed in Fig. 2, from the main drive shaft 3 through a train of gears as hereinafter described, the two shafts 3 and 72 being arranged to rotate at the same angular velocity. The drums BF and CD carried by the shafts 3 and 72 are arranged in close proximity to one another and are synchronized so that their respective peripheral notches 15 and 76 are in alignment after they pass adjacent to one another. The extending flange 74 of the corking drum CD is provided with a plurality of vertical cylindrical openings 77 as shown in Figs. 1 and 2, one of these openings being directly above and in alignment with each of the notches 76. These openings 77 are enlarged at their lower ends to a diameter greater than the outside diameter of the necks of the bottles B as clearly shown in Figs. 10 and 11.

The sleeve 73 carries a stationary circular bottle supporting platform or shelf 78, arranged to present a horizontal shelf portion 79 extending beneath the notches 76, and a vertical cylindrical wall portion 80 lying in close proximity to the extensions 75 on the drum CD. The wall portion 80 extends around substantially three-fourths of the periphery of the drum CD.

As the filled bottles are carried by the filling drum BF toward the point at which they are transferred to the corking drum CD (this point being designated at T in Fig. 2) the bottles are lowered to a position in which their upper ends are below the level of the flange 74 on corking drum CD, this being accomplished by a downwardly inclined or lowered portion 81 on the horizontal portion 22 of a bottle supporting shelf S which surrounds the bottle filling drum BF. The lowered portion 81 of the shelf S overlaps a horizontal lowered portion 79' of the supporting table 78 of the corking mechanism at the transfer point T as clearly shown in Fig. 3. At the transfer point T the horizontal supporting wall 23 of the filling mechanism ends, and a movable finger 82, pivoted at 83 and biased by the spring 84, bears against each bottle and movably retains it in its proper position during the transfer operation. An opening 85 is provided in the horizontal bottle supporting wall 80 of the corking mechanism at the transfer point T, and two tapered transfer fingers 86 and 87 are suitably secured

to one edge of this wall and extend over the opening 85 as shown in Figs. 3, 4 and 5. The fingers 86 and 87 are provided with pointed ends which extend respectively into a peripheral groove 16, and below the lower of two strips 13 on the filling drum BF, and in close proximity to the cylindrical surface of this drum, as clearly shown in Figs. 4 and 6.

As the two drums rotate, each bottle in turn is carried by the tapered fingers 86 and 87 out of a notch 15 on the filling drum BF and into a notch 76 on the corking drum CD, the bottle being held steadily in an upright position during the transfer operation by the spring pressed finger 82, and moving to a position beneath an opening 77 in the flange 74 of the corking drum. This transfer operation has been shown in Figs. 4 and 5, Fig. 4 showing the relative positions of the drums at which the fingers 76 and 78 first engage the bottle B, and Fig. 5 showing the bottle as it enters the slot 76 on the corking drum CD.

After the transfer operation, the continued rotation of the corking drum CD brings each bottle in turn up an inclined surface 88 on the horizontal portion 79 of the table 78, this surface moving the bottle upward and inserting the neck thereof into the enlarged lower portion of the opening 77 in the flange 74, as shown in Fig. 11. The bottle is now in position for the corking operation.

The upper surface of the corking drum CD is provided with a plurality of sectors 89, one for each of the openings 77 in the flange 74, these sectors being pivotally secured to the drum CD in a suitable manner at the point 90 to move over the surface thereof, as shown in Fig. 2. Each sector 89 is provided with a roller or cam follower 91 secured to the inner corner thereof, and extending upwardly into a cam groove 92 in a stationary cam plate 93. The cam plate 93 is rigidly supported above the drum CD by means of the brackets 94, 95 and 96 as shown in Figs. 1 and 2. Each sector 89 also carries a vertically extending sleeve 97 carrying a corking plunger 98 which is normally held in its retracted or upper position by a spring 99 as clearly shown in Fig. 11. The upper end of the plunger 98 is provided with a suitable anti-friction bearing such as the ball bearing 100. The extreme outer corner of each sector 89 is formed into a hook shaped extension 101 having an internal radius substantially equal to the radius of the openings 77 in the flange 74 of the corking drum. The under surface of the sector 89 is cut away beneath the extension 101 and the plunger 98 as clearly shown in Figs. 7, 9 and 11.

The bracket 94 is provided with a vertical tubular portion 102 carrying a cork feed tube 103. Bottle corks C of a suitable type are continuously fed through the feed tube 103 with their tapered ends downward by a suitable cork arranging and feeding mechanism. A

cork feeding mechanism suitable for this purpose is shown and described in my co-pending application Serial No. 292,257, filed July 12, 1928. A pivotally mounted lever 104 is fixed to a shaft 105 journaled in the bracket 94, this lever being biased in a clockwise direction, as viewed in Fig. 7, by a spring 106 as shown. The lever 104 carries a pin 107 which extends through aligned openings in the tubular portion 102 and the feed tube 103, and holds the lowest cork stationary in the end of the feed tube. A finger or trigger 108 is fixed to the lower end of the shaft 105 and extends over the extensions 75 on the drum CD in a position to be engaged by a bottle as it is carried around by the drum, the normal position of this trigger being best shown in Fig. 7.

As a bottle is carried around by the drum, it engages the trigger 108, moving the lever 104 a distance sufficient to permit the pin 107 to release one cork C from the feed tube 103, the trigger, lever and pin then being returned by the spring 106 to hold the next cork C in the end of the feed tube. The released cork is dropped on the top of the flange 74 near one of the openings 77. As the drum continues to rotate, the cork C is held against movement therewith by an arm 109 of a bell crank lever 110, pivotally supported on the bracket 94 as shown, and having a notch 111 provided in the outer end of the arm 109 for the reception of the cork C. The outer arm 112 of the bell crank lever 110 is provided with a downwardly offset roller 113 adapted to bear against the outer edge of the flange 74, a spring 114 being provided to bias the bell crank lever to the position shown in Figs. 7 and 9. The peripheral edge of the flange 74 is provided with a plurality of outwardly extending trips 115, disposed to engage the roller 113 of the bell crank lever 110 and to quickly snap this lever outwardly as the drum CD is rotated, each trip 115 being disposed adjacent one of the openings 77 in the flange 74, in such a position that the lever 110 is snapped out just as the opening 77 is aligned with the notch 111 in the arm 109.

The cam groove 92 in the stationary cam plate 93 runs parallel to the periphery of the drum CD up to a point just beyond the bracket 94 in the direction of the rotation of the drum, and is spaced a distance from the edge of the flange 74 such that each of the sectors 89 is maintained in a position with its hooked extension 101 aligned with one of the holes 77 in the flange until such sector has passed the bracket 94. As the drum CD rotates, and a bottle approaches the bracket 94, the trigger 108 is engaged and pushed outwardly by the wall of the bottle, releasing a cork C from the tube 103, the remaining corks being retained in the tube by the pin 107 as the trigger 108 is released by the bottle and the lever 104 is returned to its normal position by the spring

106. The cork C drops on the flange 74 and is held against movement therewith by the arm 109 of the bell crank lever 110, the cork resting in the notch 111 at the end of this arm. As the drum continues to rotate, the hooked extension 101 on the sector 89 engages the cork, this extension together with the arm 109 serving to center the cork above the opening 77. At this point in the rotation of the drum, the trip 115 engages the roller 113 of the bell crank lever 110, snapping this lever outwardly and swinging the arm 109 away from the cork C, thus permitting the cork to drop through the opening 77 and into the neck of the bottle B.

The cam groove 92 is so formed as to move each sector 89 outward after the cork C has been dropped through the corresponding opening 77, the sector being thus moved until the corking plunger 98 is directly over the opening 77 as shown in Fig. 11. Shortly after the sector under consideration is moved to this position, the anti-friction ball bearing 100 on the upper end of the plunger 98 is engaged by a cam surface 116 which forces the plunger downward, thus forcing the cork C securely into the neck of the bottle B as shown in Fig. 3. The cam surface 116 is curved to conform with the path of travel of the plunger as shown in Fig. 2, and is suitably secured to a supporting bracket 117 which is slidably carried by the vertical support 118. A vertical adjusting screw 119 is journaled in the stationary bracket 96 and has a screw threaded engagement with the bracket 117, thus permitting the vertical adjustment of the cam surface 116 to vary the depression of the plunger 98. A set screw 120 is preferably provided in the bracket 117, by means of which this bracket may be clamped to the support 118 after adjustment.

A modified form of corking plunger and cam surface is shown in Fig. 12. In this modification, the upper end of the plunger 98 is offset and is provided with a horizontally disposed roller 121 which is engaged by a cam groove or slot 122 in the member 123. The member 123 is secured to the bracket 117 and operates the plunger 98 positively, that is, lifts this plunger out of the opening 77 as well as inserting it therein. The modification of Fig. 12 has a certain advantage over the plunger and cam surface arrangement shown in Figs. 3 and 11, in that this modified form prevents the possibility of the plunger 98 becoming stuck or jammed in its depressed position, which condition might possibly occur due to the collection of dirt or abrasive matter within the sleeve 97.

After the corks C have been inserted and pressed into the bottles, each bottle in turn is lowered to a position in which its neck and cork are withdrawn from the opening 77 in the flange 74, this being accomplished by the lower ends of the bottles passing down

80

85

90

100

105

110

115

120

125

130

an incline 63 in the horizontal portion 79 of the table 78. Each bottle in turn is then picked off of the drum by means of the fingers 124 and 125 which are disposed in close proximity to the surface of the drum CD above and below the extensions 75 respectively. The fingers 124 and 125 guide the bottles into a discharge chute 126 from which they are pushed into a suitable container, not shown.

The bottle filling drum is carried by a shaft 3 which is driven through a worm gear 9, a suitable source of power being connected to this gear. A gear 288 is fixed to the shaft 3 below the platform 1 and engages a gear 289 carried by a stub shaft 290. The gear 289 engages a second gear 291 which in turn engages a gear 292 fixed to the shaft 72, whereby this shaft is rotated by the shaft 3.

The gears 288, 289, 291 and 292 are of such a size that the shafts 3 and 72 are rotated at the same angular velocity.

The shaft 72 carries a beveled gear 293 fixed thereto and engaged by a bevel pinion 294, fixed to a shaft 295 carried by a bracket 296. The shaft 295 carries a hand wheel 297 suitably secured thereto so that the entire machine may be slowly moved by hand through the operation of this wheel. This manual operation of the machine is advantageous when it is desired to change the relative positions of certain of the moving parts of the mechanism for the purpose of cleaning or repairs. When the main source of power is cut off, and the machine operated by hand, the worm gear 9 remains stationary, the pawl and ratchet 12 permitting the shaft 3 and the remaining drive mechanism and moving parts to be moved in their normal direction independently of the source of power.

The present invention has been described in connection with a single specific machine, and it should be clearly understood that the invention is not limited to the exact mechanical details or expedients shown, and that certain modifications, changes and omissions may be made in the machine without departing from the scope of the invention as defined in the appended claims.

I claim:

1. In a bottle filling and corking machine, a revolving corking drum having notches on the peripheral edge thereof for carrying bottles, a flange on said drum extending over said notches and having openings therein aligned with said notches, means for continuously feeding filled bottles into the notches of said drum, means for inserting the upper ends of said bottles into the openings in said flange, means adjacent said drum actuatable by the approach of a bottle to drop a cork on said flange adjacent each of said openings, a movable sector carried by said drum, and a stationary cam adjacent

said drum for moving said sector to guide said cork into said opening.

2. In a bottle filling and corking machine, a revolving corking drum having notches on the peripheral edge thereof for carrying bottles, a flange on said drum extending over said notches and having openings therein aligned with said notches, means for continuously feeding filled bottles into the notches of said drum, means for inserting the upper ends of said bottles into the openings in said flange, means for successively dropping said corks on said flange adjacent said openings, a pivotally mounted lever adjacent said drum for guiding each cork into one of said openings, and a plunger carried by said drum adjacent each of said openings for forcing each cork into its corresponding bottle.

3. In a bottle filling and corking machine, a revolving corking drum having an extended peripheral flange with openings therein, means on said drum for carrying a plurality of bottles around the periphery thereof with their necks aligned with said openings, means for dropping a cork adjacent each of said openings, a sector pivotally mounted on said drum adjacent each of said openings, a notch in said sector for guiding a cork into said opening, a plunger carried by said sector, stationary means adjacent said drum engaging said sector for moving said plunger over said opening, and means for operating said plunger to insert the cork into the bottle.

4. In a bottle filling and corking machine, a revolving bottle corking drum, a plurality of, bottle carrying notches on said drum means for continuously feeding filled bottles to said notches as said drum rotates, means for dropping a cork into the neck of each bottle, and means for forcing the cork into each bottle comprising a sector pivotally mounted on said drum adjacent each of said notches, a plunger carried by said sector, stationary means for moving said sector over said notch until said plunger is aligned with the cork in a bottle, and means comprising a stationary cam surface supported over said drum for depressing said plunger and forcing said cork into the bottle as the drum rotates.

5. In a bottle filling and corking machine, a rotary corking drum having a plurality of bottle carrying notches on the peripheral edge thereof, a flange on said drum overhanging said notches and having an opening therethrough over each of said notches, means for continuously feeding filled bottles to said notches as the drum rotates, a stationary bracket adjacent said drum carrying a cork feed tube, pivotally mounted means carried by said bracket and successively engageable by the bottles carried by said drum for dropping a cork from said feed tube to said flange at a point adjacent each of said openings, a lever on said bracket for hold-

ing said cork from rotation with said drum, and means on the flange of said drum for moving said lever to drop said cork through one of said openings into one of the bottles.

6. In a bottle filling and corking machine, a rotary bottle corking drum having means thereon for carrying a bottle at the peripheral edge thereof, means for feeding a bottle to said bottle carrying means, a flange on said drum over said bottle having an opening therein aligned with said bottle, a stationary bracket adjacent said drum carrying cork feeding means actuatable by the approach of said bottle to drop a cork on said flange adjacent said opening therein, means for guiding said cork into said opening comprising a lever carried by said bracket and a sector pivotally mounted on said drum, a plunger carried by said sector, a stationary cam engaging said sector for moving said plunger over said opening, and a second stationary cam extending above the path of travel of said plunger and acting to depress said plunger through said opening and thereby force said cork into said bottle as the drum rotates.

7. In a bottle filling and corking machine, a rotary corking drum for carrying a plurality of filled bottles, means for dropping a cork into each of said bottles and means for forcing said corks into said bottles comprising a plurality of plungers carried by said drum, means for moving said plungers into alignment with said bottles after the corks have been dropped therein, and a stationary cam adjacent said drum for depressing said plungers.

8. In a bottle filling and corking machine, a rotary corking drum for carrying a plurality of filled bottles, means for dropping a cork into each of said bottles and means for forcing said corks into said bottles comprising a plurality of plungers carried by said drum, means for moving said plungers into alignment with said bottles after the corks have been dropped therein, a stationary cam supported above said drum for depressing said plungers, and means for adjusting the position of said cam to vary the distance said plungers are depressed.

9. In a bottle corking machine, a rotary corking drum, means for carrying a plurality of bottles on said drum, openings in the upper surface of said drum aligned with said bottles, means for dropping a cork into each of said bottles through said openings and means for forcing said corks securely into said bottles comprising a plurality of plungers movably carried by said drum, means for moving said plungers into alignment with said openings after said corks have been dropped therethrough, and a stationary cam adjacent said drum for successively moving said plungers into said openings and withdrawing them therefrom.

10. In a bottle corking machine, a rotary corking drum, means for carrying a plurality of bottles on said drum, openings in the upper surface of said drum, aligned with said bottles, means for dropping a cork into each of said bottles through said openings and means for forcing said corks securely into said bottles comprising a plurality of plungers movably carried by said drum, means for moving said plungers into alignment with said openings after said corks have been dropped therethrough, rollers carried by said plungers, and a stationary block having a cam groove therein supported adjacent said drum for engaging said rollers and forcing said plungers into and out of said openings.

11. In a bottle filling and corking machine, a rotary corking drum having notches thereon for carrying bottles, means for continuously feeding bottles into said notches as said drum rotates, a stationary bottle supporting shelf adjacent said drum for retaining said bottles in said notches as said drum rotates, a flange on said drum overhanging said notches and having openings therein aligned with said notches, means adjacent said drum for dropping a cork into each of said bottles through said openings, sectors pivotally supported on said drum adjacent each of said openings, means on said sectors for guiding said corks into said openings, cork depressing plungers carried by said sectors, a stationary cam plate supported above said drum for moving said sectors to a position in which their plungers are aligned with said openings after said corks have been dropped therethrough, and a second cam adjacent said drum for successively depressing said plungers to force said corks into said bottles.

12. In a bottle filling and corking machine, a revolving corking drum having notches on the peripheral edge thereof for carrying bottles, a flange on said drum extending over said notches and having openings therein aligned with said notches, means for continuously feeding filled bottles into the notches of said drum, means for inserting the upper ends of said bottles into the openings in said flange, means adjacent said drum actuatable by the approach of a bottle to drop a cork on said flange adjacent each of said openings, a movable sector carried by said drum, stationary means adjacent said drum for moving said sector to guide said cork into said opening and means carried by said sector for forcing the cork guided by the sector into the bottle.

In testimony whereof I affix my signature.

NICOLA F. SAVIANO.
